Loyd G. Dorsett, Norman, Okla., assignor to Dorsett Industries, Inc., Norman, Okla., a corporation of Oklahoma

Filed Jan. 30, 1967, Ser. No. 5,610

Term of patent 14 years

(Cl. D25—1)

FIG. 1 is a side, top and front perspective view of an audio-visual tutoring device, showing my new design;

FIG. 2 is an opposite side, bottom and rear perspective view;

FIG. 3 is a front elevational view;

FIG. 4 is an end elevational view;

FIG. 5 is a top plan view; and,

FIG. 6 is a sectional view taken along line 6—6 of FIG. 3.

Portions of FIGS. 1 and 3 are diagonally lined to indicate translucency. The grills fragmentarily shown in FIGS. 1 and 3 are continuous within the boundaries indicated.

I claim:

The ornamental design for an audio-visual tutoring device, as shown and described.
